Fig. 1

Fig. 2

Fig. 3

Fig. 4

FIG. 1 is a perspective view of a surgical tray showing my new design therefor;

FIG. 2 is a top plan view thereof;

FIG. 3 is a side elevational view thereof; and

FIG. 4 is an end elevational view thereof.

The characteristic feature of my design resides in the specific arrangement of the compartmented wall members, as best illustrated in FIGS. 1 and 2 in the drawing.

I claim:

The ornamental design for a surgical tray, substantially as shown and described.
